No. 829,493.

PATENTED AUG. 28, 1906.

W. R. THURSTON.
ORE CONCENTRATOR.
APPLICATION FILED OCT. 9, 1905.

UNITED STATES PATENT OFFICE

WALTER R. THURSTON, OF DOUGLAS, ARIZONA TERRITORY.

ORE-CONCENTRATOR.

No. 829,493.

Specification of Letters Patent.

Patented Aug. 28, 1906.

Application filed October 9, 1905. Serial No. 281,967

To all whom it may concern:

Be it known that I, WALTER R. THURSTON, a citizen of the United States, residing at Douglas, in the county of Cochise and Territory of Arizona, have invented certain new and useful Improvements in Ore-Concentrators, of which the following is a full, clear, and exact description, reference being had to the accompanying drawings, forming a part hereof.

My invention has relation to improvements in gravity-concentrators (for the treatment of ore or any other material;) and it consists in the novel construction and arrangement of parts more fully set forth in the specification and pointed out in the claims.

In the drawings, Figure 1 is a middle vertical section of my concentrator, parts being shown in elevation. Fig. 2 is a horizontal section on the broken line 2 2 of Fig. 1, parts being broken away to expose portions beneath them. Fig. 3 is a sectional detail on the horizontal line 3 3 of Fig. 1, showing the controlling-valve of the discharge-spout for the concentrates, coarse or fine. Fig. 4 is an enlarged detail showing ball-and-socket connection between the eccentric-rod of the drive-shaft and the hub of the spider supporting the pan, and Fig. 5 is a perspective of a small section of the annular water trough or box carried by the pan.

The present apparatus is an improvement on the ore-concentrator forming the subject-matter of my pending application, Serial No. 270,856, filed July 22, 1905, and contemplates certain qualifications of construction which will not only enlarge the possibilities of the concentrator and secure an increased efficiency therefor, but will impart thereto specific advantages which result directly from the qualifications of construction referred to. Among these may be mentioned the provision of suitable mechanism which imparts a vertically-reciprocating movement to the oscillating pan, the presence of a baffle or deflecting plate to deflect the flow of the material passing into the overflow-hopper, a wash-water pipe supplying water to assist in the washing of the lighter tailings and gangue, a water-box to supply water for bringing the pulp to proper consistency, the corrugation of the pan-walls to secure a longer travel for the particles of mineral, a dividing-ring to grade the concentrates, suitable shields over the concentrate discharge-spouts, and other details whose specific advantages will be bet-

ter apparent from the detailed description of the invention which is to follow. These qualifications in no wise affect the general objects of the invention as expressed in the pending application, the purposes of the present improvement being the same, all as will more fully hereinafter appear.

In detail the invention may be described as follows: Referring to the drawings, F represents a suitable frame constructed, preferably, of angle-iron, which supports the operating parts of the apparatus. Resting on a bed-plate 1 at the center of the base of the frame is a stationary vertical shaft or staff S having an upper terminal reduced square portion 2, passed through a top member of the frame, the bottom of the shaft being secured additionally by a set-screw 3, so that the shaft is absolutely rigid and stationary. Passed over the square terminal 2 and resting on the shoulder formed between it and the body of the shaft S is a spider 4, to which is secured a feed-hopper 5, the lower portion of the peripheral walls of the hopper being provided with openings 6, which discharge the pulp from the hopper onto a conical disk or distributor 7, secured to the hopper, the pulp running over the outer edges of the distributor and discharging at points contiguous to the outer edges of the oscillating pan 8.

The concave walls of the pan are preferably corrugated, the corrugations being disposed in concentric circles about the axis of oscillation of the pan, the object of the corrugations being to secure a greater surface over which the particles of mineral may travel, thereby securing a better separation of the material to be concentrated and allowing more time for the motion of the pan to take effect on the pulp. The pan may be made of cast or pressed steel or iron, wood, fiber, glass, rubber, or composition, or other suitable material adapted for the purpose, but preferably of steel, with a lining of enamel or rubber to insure adhesion of the finer particles of mineral thereto. The pan envelops the shaft S and is rotatably supported about the same through the medium of a supporting-spider 9, the hub 9' of which loosely embraces the shaft S.

Adjustable along the shaft and encompassed by the pan is an overflow-hopper 10, which has formed therewith a central sleeve 11, enveloping and protecting the shaft, the adjustment of the hopper being effected by moving the adjustable collar 12 along the

shaft to proper position, then securing the collar by means of the set-screw 13, the hopper resting on the collar thus adjusted. The base of the hopper is provided with a block 14, which rests directly on the collar 12 referred to. Since the overflow hopper is adjustable relatively to the pan, suitable provision must be made for a water-tight joint between the parts, and this is accomplished by means of the stuffing-box 15, as shown. Leading from the bottom of the overflow-hopper is a discharge-spout 16, which conveys the waste overflow or tailings into a launder 17.

15 Mounted in suitable bearings 18 18 at the bottom of the frame F is a drive-shaft 19, provided with tight and loose pulleys P P', respectively, driven by a belt B, leading to any source of power. (Not shown.) At one 20 end of the drive-shaft is an eccentric-disk 20, about which is loosely passed the strap 21 of an eccentric-rod 22, the opposite end of the latter loosely embracing the spherical head 23 of a ball-pin 24 at the outer end of the arm 25 or boss 25, projecting from the hub 9' at the base of the spider 9, the ball-pin being provided with a jam-nut 26. This connection forms a ball-and-socket joint, allowing the pan not only to freely oscillate about the axis 30 of the shaft S as a center, but to reciprocate vertically during its oscillating movements. The vertical reciprocation of the pan is accomplished by the following mechanism: Disposed along the drive-shaft 19 is an eccentric 35 27, which in its rotation plays along the upper surface of the long arm of a vertically-oscillating lever 28, supported in the fulcrum-bearings 29 29 on the bed-plate, the short arm of the lever being in the form of a fork 30 30, encompassing a lifting-block 31, loosely mounted over the shaft S, the block being provided with diametrically-opposite radially-projecting pins 32, loosely embraced by the brasses 33, mounted in the bifurcated ends of each of the fork members 30. 40 As the drive-shaft 19 therefore rotates the eccentric 27 will with each revolution of the shaft depress the long arm of the lever 22, raising the opposite arm, and thus lift the block 31 along the shaft, the block gravitating back to its original position against the bearing 1' of the base-plate the moment the eccentric formation of the cam has passed off the lever. Since, however, the block 31 directly 45 supports the spider 9 and pan 8, it follows that the pan will have a vertically-reciprocating movement imparted thereto simultaneously with its horizontal oscillations about the shaft S.

50 Disposed beneath the distributor and contiguous to the outer edge thereof and above a marginal annular inwardly-inclined ledge 34 is a circular perforated wash-water pipe 35, coupled to a water-supply pipe p, the purpose of the wash-water being to assist in

washing over the lighter tailings or gangue matter into the overflow-hopper 10. The water from the pipe 35 escapes through a series of perforations, distributing itself evenly along the ledge 34 and discharging 50 into the pan. To effectively deflect the flow of the material passing into the overflow-hopper, the present apparatus is provided with an adjustable deflector or baffle 36, being in the form of a flanged disk which is provided with a central hollow or tubular stem 37 loosely embracing and passing beyond the sleeve 11 and clamped adjustably along the shaft S by means of a screw 38. In this manner the baffle may be adjusted vertically according to the height of the liquid flowing into the pan.

In order that the pulp may be regulated in the matter of consistency and that proper consistency may at all times be secured therefor, provision is herein made in the form of an annular trough or water-box 39 at the outer edge of the pan, the bottom of the box being perforated, Figs 2 5, to allow the water to mix with the pulp. The water may be supplied to the trough from any source, (not shown,) and the trough may either wholly, as shown, or only partially encircle the pan.

In order that I may separate the lighter from the heavier concentrates which settle at the bottom of the pan, I intercept the latter by means of a dividing wall or ring 40, leading such heavier particles out by means of a concentrate-valve, to be presently referred to. The finer concentrate particles will pass over this ring and be caught outside of the overflow-hopper, whence they can be withdrawn through the concentrate-spout 41, leading from the pan between the overflow-hopper and the dividing-ring. Over the concentrate-discharge opening (or openings, if there be more than one) I secure a shield 42, the presence of which prevents the formation of depressions directly over the discharge-opening as the concentrates are being drawn off. It is obvious that the presence of such depressions results in the production of disturbing currents, which are objectionable in the course of the concentrating operation. The presence of the shields 42 insures a uniformity in distribution of the material, as it settles along the bottom of the pan. The shields 42 are preferably secured to the wall of the overflow-hopper 10, as shown.

As in my pending application above referred to the concentrate-discharge spout 41 is controlled by a valve 43, pivoted to a bracket 44, carried by the spout, the inner or valve end of the valve being held in a closed position by the retracting action of a coiled spring 45, whose one end is secured to the outer arm of the valve and whose opposite end is secured to the bracket 44. As the pan oscillates with each alternate stroke the terminal lug 46 of the valve strikes the adjacent

end of an adjustable tappet-screw 47, carried by an arm 48 on the frame F. In thus striking the tappet 47 the latter oscillates the valve 43 sufficiently to open the discharge end of the spout 41, allowing the finer concentrates to be intermittently discharged into a trough 49. With the return stroke of the pan the valve passes out of the influence of the tappet 47, leaving the spring 45 to close the valve. By adjusting the tappet 47 the extent of oscillation of the valve may be correspondingly adjusted according to the requirements in any particular case. The discharge-spout 50 for the coarse concentrates, located just outside of the dividing-ring 40, is or may be controlled by the same construction of valve, the parts thereof being identified by the same reference-numerals in the drawings. The spout 50 discharges into a trough 51.

The operation of the device is identical with that described in my pending application referred to, except that in addition to the oscillating motion the pan has a vertically-reciprocating movement. The wet pulp delivered to the hopper 5 flows down through the openings 6 onto the distributor or disk 7, where it flows into the pan at points contiguous to the outer edge thereof or points of greatest agitation, mingled if desirable with the waters from the wash-water pipe 35 and the trough 39. As the drive-shaft 19 rotates it imparts an oscillating motion to the pan (and overflow-hopper) about the axis of the shaft or staff S and a simultaneous vertically-reciprocating movement along said axis, the points nearest the shaft being of course subjected to a minimum oscillatory speed or agitation, as it is desirable that at such points the lighter waste or tailings be subjected to the least amount of agitation. These tailings, as above stated, are deflected and constrained to pass under water before passing into the overflow-hopper by the baffle 36. The pulp as it enters the pan (see three tailed arrows in Fig. 1) becomes agitated, the tailings or waste overflowing into the overflow-hopper 10 and out through the spout 16 into the launder 17. (See feathered arrows.) The concentrates grade themselves according to specific gravity, the coarser particles remaining outside the dividing-ring 40, whence they are withdrawn through the spout 50, and the lighter and finer concentrates passing over the dividing wall or ring and settling between it and the overflow-hopper, whence they are withdrawn through the spout 41. (See plain arrows.)

As in my pending application referred to so in the present case the material enters the pan at points of greatest oscillatory speed and agitation, thereby initially and effectively separating the concentrates from the tailings, the material being gradually subjected to less and less agitation, allowing the

waste to be withdrawn near the axis of oscillation of the pan, where a minimum amount of oscillation takes place. Likewise are the concentrates removed from the pan at points where the oscillatory agitation is comparatively reduced and where any material not drawn through the overflow-hopper has time to settle. The oscillatory motion at the outer edge of the pan, produced through the eccentric-rod connection between the hub 10 and drive-shaft 19, amounts to only about two or three inches, the vertical movement of the pan during its oscillations being considerably less, though I do not wish to limit myself to any specific relation between the distances traversed in these movements.

Having described my invention, what I claim is—

1. In a concentrator, a suitable pan having a concave bottom, means for imparting thereto an oscillating movement in a given plane about a fixed axis, a block disposed about the axis of oscillation of the pan and having a reciprocating motion of translation along said axis, an oscillating lever in coöperative connection with said block for imparting thereto the motion aforesaid, and connections between the block and pan whereby a corresponding reciprocation is imparted to the pan along its axis of oscillation, substantially as set forth. 85
2. In a concentrator, a suitable pan having a concave bottom, means for imparting thereto an oscillating movement in a given plane about a central axis, a member disposed about the axis of oscillation of the pan and having an oscillating motion in a plane parallel to such axis, and a block disposed about said central axis and interposed between said member and pan for imparting to the latter a reciprocating motion of translation along its axis of oscillation, substantially as set forth. 90
3. In a concentrator, a suitable pan having a concave bottom, means for imparting thereto an oscillating movement in a horizontal plane about a central vertical axis, a lever having one end disposed about said axis and having an oscillating motion parallel thereto, a block interposed between said pan and lever and having imparted thereto by said lever a reciprocating motion of translation along the axis of oscillation of the pan, whereby a corresponding reciprocation is communicated to the pan, substantially as set forth. 110
4. In a concentrator, a suitable concave-bottomed pan oscillating about a fixed axis and having an axial vertically-rectilinear reciprocating movement, a distributor delivering the material thereto at points contiguous to the outer edge of the pan, a perforated wash-water pipe disposed adjacent to the outer edge of the distributor, and a guiding-ledge for the water discharged from said pipe, substantially as set forth. 120
5. In a concentrator, a suitable concave- 130

- bottomed pan oscillating horizontally about a central vertical axis, a supporting-block movable rectilinearly along said axis and imparting to the pan at the axis, a reciprocating motion of translation in a plane at right angles to its plane of oscillation and an oscillating lever for actuating the block, substantially as set forth.
6. In a concentrator, a suitable pan oscillating about a fixed axis, a distributer delivering the material thereto at points contiguous to the outer edge of the pan, an inwardly

and downwardly inclined ledge disposed about the edge of the distributer, and a perforated wash-water pipe confined between the ledge and distributer and discharging its water over the ledge into the pan, substantially as set forth.

In testimony whereof I affix my signature in presence of two witnesses.

WALTER R. THURSTON.
